US00D849604S

(12) **United States Design Patent** (10) Patent No.: **US D849,604 S**
(45) Date of Patent: **** May 28, 2019**

(54) **ELECTRO-TRICYCLE**

(71) Applicant: **CHONGQING YINGANG TECHNOLOGY (GROUP) CO., LTD.**, Chongqing (CN)

(72) Inventor: **Yi Wu**, Chongqing (CN)

(73) Assignee: **CHONGQING YINGANG TECHNOLOGY (GROUP) CO., LTD.**, Chongqing (CN)

(**) Term: **15 Years**

(21) Appl. No.: **29/629,313**

(22) Filed: **Dec. 12, 2017**

(30) **Foreign Application Priority Data**

Jun. 14, 2017 (CN) 2017 3 0242593

(51) LOC (11) Cl. **12-02**

(52) U.S. Cl.

USPC **D12/128**

(58) **Field of Classification Search**

USPC D12/128-133

CPC A61G 5/04; A61G 5/041-5/047; A61G 2005/048

See application file for complete search history.

(57) **CLAIM**

The ornamental design for an electro-tricycle, as shown and described.

DESCRIPTION

FIG. 1 is a front view of an electro-tricycle, showing my new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof;

FIG. 8 is a second perspective view thereof;

FIG. 9 is a third perspective view thereof; and,

FIG. 10 is a fourth perspective view thereof.
